UNITED STATES PATENT OFFICE.

WILLIAM J. REAGAN, OF ROYER'S FORD, PENNSYLVANIA, ASSIGNOR TO
ROYER'S FORD IRON FOUNDRY, OF SAME PLACE.

DESIGN FOR SAD-IRON HANDLES.

Specification forming part of Design No. **7,967**, dated December 29, 1874; application filed November 4, 1874.
[Term of Patent 14 years.]

To all whom it may concern:

Be it known that I, WILLIAM J. REAGAN, of Royer's Ford, Montgomery county, and State of Pennsylvania, have invented a Design for the Handle of a Sad-Iron, of which the following is a specification:

The figure in the accompanying drawing illustrates my design for the handle of a sad-iron, the line *x x* representing the upper surface of the body of the iron and the termination of the handle.

The opening *A*, for the admission of the hand, is made in the form of an ellipse, the continuity of which is interrupted by the grip *a*, the latter being made circular, and of the shape shown. The ends *b b* of the handle con-

form to the shape of the opening, excepting at the bottom *y*, where they terminate in the curves shown.

I claim—

The design for a sad-iron handle, including the elliptical opening *A* and grip *a*, as described, and as illustrated in and by the accompanying drawing.

In testimony whereof I have signed my name to this specification in the presence of two subscribing witnesses.

WM. J. REAGAN.
